[57] CLAIM

The ornamental design for a blood pump drive console for patient support during open heart surgery, as shown.

DESCRIPTION

FIG. 1 is a rear perspective view of a blood pump drive console for patient support during open heart surgery showing my design, with the control access drawers in closed position;

FIG. 2 is a side elevational view thereof;

FIG. 3 is a top plan view thereof;

FIG. 4 is a front elevational view thereof;

FIG. 5 is a rear elevational view thereof;

FIG. 6 is a side elevational view thereof, opposite that shown in FIG. 2;

FIG. 7 is a bottom plan view thereof;

FIG. 8 is a rear perspective view thereof, with the control access drawers in open position;

FIG. 9 is a side elevational view thereof;

FIG. 10 is a top plan view thereof;

FIG. 11 is a rear elevational view thereof;

FIG. 12 is a side elevational view thereof, opposite that shown in FIG. 9; and

FIG. 13 is a bottom plan view thereof.
